CALUTRON ELECTRIC LENS

Herbert W. B. Skinner, Harwell, England

Application November 25, 1947, Serial No. 787,878

4 Claims. (Cl. 250—41.9)

1

This invention relates to the focusing of divergent ion beams and more particularly relates to improved electrostatic focusing means for increasing the sharpness of the foci of divergent arcuate ion beams in the electromagnetic separation of isotopes.

In the operation of devices which employ electromagnetic means for separating isotopes the high current ion beams generally employed are ion beams which have a virtual line source parallel to the magnetic field, and in addition have considerable divergences in a plane transverse to said magnetic field. Furthermore, whereas certain ions such as for example U^{235} and U^{238} have a theoretical foci separation at the 180° position of over two inches for ion beam radii of about 50 inches, it has been found that when employing no other focusing means than that of the uniform magnetic field, the beams will have an actual separation of less than an inch and with the degree of sharpness of focus thereby obtainable will therefore, overlap in the region of their maximum separation. Thus in order to obtain a separation of the ion beams which will approach the theoretical foci separation of about two inches, it is necessary to provide an arrangement which will divert them from their normal arcuate paths and into sharp foci in the region of their maximum separation.

In the copending application of H. W. B. Skinner, Serial No. 787,877, filed November 25, 1947, there is described an electrostatic focusing arrangement consisting of four parallel spaced substantially identical overlying decks, each deck being comprised of a shield shaped central plate electrode nested within similarly curved and successively nested strip electrodes. Those electrodes in successive decks which are identical and their edges being in a common magnetic projection are electrically connected to a source of potential with the exception of the outermost strip electrodes which are grounded to the calutron tank in which the electrostatic lens is mounted. Working inwardly from the outermost strip electrodes, successively adjacent sets of electrically connected electrodes are, each in turn, connected to a source of potential of value and sign determined by design considerations. The series of curvilinear edges of adjacent nested electrodes set up, in accordance with the respective potentials applied to these electrodes, a series of nested equipotential surfaces similarly curved; said equipotential surfaces being disposed transversely to the path of the divergent arcuate ion beam. The relative strength and configuration of the equipotential surfaces encountered by the

2

ion beam divert the component ions thereof through a series of small angular deflections, thereby directing ions having equal mass to charge ratios to a common focus.

The present invention concerns an electric lens similar in certain respects to the electric lens described in the foregoing, however, present improvements are incorporated to further reduce the ion absorption of the lens structure by providing vertical focusing of the ion beam at the leading focusing elements so that fewer ions in their arcuate traverse will impinge the trailing focusing elements.

It is therefore an object of the invention to improve the electromagnetic separation of isotopes by increasing the sharpness of foci of divergent arcuate ion beams.

It is a further object of this invention to improve the sharpness of foci of divergent arcuate ion beams in the electromagnetic separation of isotopes beyond the sharpness which can be obtained through the effect of the magnetic field alone.

It is a further object of this invention to increase the sharpness of foci of divergent arcuate ion beams by imposing equipotential surfaces in the path of said ion beams.

A further object of this invention is to minimize the ion absorption of the electrostatic lens system by use of leading and trailing electrodes wherein the leading electrodes produce a certain amount of vertical focusing of the ion beam, the trailing electrodes being planarly offset relative to the leading electrodes thereby being positioned in a region of the ion beam having minimum ion density.

Other objects and advantages of the invention will be apparent in the following description and claims considered together with the accompanying drawings in which:

40 Figure 1 is a plan view of the calutron tank with the top plate removed showing the electrostatic lens positioned therein with relation to the ion transmitter, the divergent arcuate ion beam, and the ion receiver.

45 Fig. 2 is a partial front elevational section as indicated by section line 2—2 in Fig. 1 showing the electrostatic lens assembly mounted on the bottom plate of the calutron tank by means of insulators.

50 Referring now to Figs. 1 and 2, there is illustrated the present type of electric lens as disposed in a calutron. The lens 11 is positioned near the rear wall 12a of the calutron tank 12 midway between the ion transmitter 13 and the ion receiver 14; the ion transmitter 13 and the ion

receiver 14 being mounted on the front wall 12b of tank 12. The tank 12 is disposed between the pole faces of a magnet, the magnetic field thereof passing transversely through the top wall 12d and the bottom wall 12c. The direction of said field is indicated by arrows as shown in Fig. 2. The electric lens assembly 11 (see Fig. 2) is mounted on the bottom wall 12c of the calutron tank 12 by means of electrical insulators 16 which in turn attach to conducting and supporting uprights 17. The lens 11 consists of upper and lower substantially identical shield shaped plate electrodes 18 which are normal to the magnetic field of the calutron and which have disposed between them two sets of parallel strip electrodes 19 and 20 having their outer edges of the same configuration as, and parallel to, the respective peripheral edges of the electrodes 18. Moreover, the electrodes 19 are staggered along the magnetic field with respect to the electrodes 20. Auxiliary sets of parallel strip electrodes 22 and 23 are positioned adjacent to the outer edges of the electrodes 19 and 20, the electrodes 22 being coplanar with the electrodes 19 and the electrodes 23 being coplanar with the electrodes 20. The adjacent edges of the electrodes 19 and 22, and the electrodes 20 and 23, respectively, define the electrostatic refracting regions of the electric lens 11.

Considering now the electrical connections of lens 11, there are three components insulated from one another, comprising: electrodes 22 interconnected by their conducting uprights 17; plate electrodes 18, electrodes 19 and 20 interconnected by their respective conducting uprights 17; and electrodes 23 also interconnected by conducting uprights 17. The three components described are connected to different sources of electrical potential, each potential 21 being of proper value and sign as predetermined by design considerations.

In operation, the divergent arcuate ion beam in passing through the region encompassed by the electrostatic lens encounters a series of equipotential surfaces substantially of a configuration defined by the magnetic projection of the edges of the various electrodes. These equipotential surfaces vary in relative strength in accordance with the potentials to which the various electrodes are charged. Depending upon the angle of incidence at which the component ions of the ion beam encounter the described equipotential surfaces and also upon the electrical field strengths of these surfaces, those ions having equal mass to charge ratios are diverted from their normal trajectories and directed to a common initial focus in the region of the ion receiver. Further, the field set up by electrodes 19 and 22 of the lens 11 causes a vertical focusing of the ion beam along the planes of electrodes 19 and 22, whereby due to the offset positioning of electrodes 20 and 23 the greatest ion density will occur midway of the spaces between successive planar decks of electrodes 20 and 23 and thereby will result in a decreased ion beam absorption by the electric lens 11.

The important improvement embodied in the present invention over electric lenses of the type comprising multiple strip electrodes arranged in overlying planar decks disposed transverse to the magnetic field, lies in the offset along the magnetic field of the trailing electrodes with respect to the leading electrodes, whereby the overall ion absorption of the lens is reduced by a decrease in the ion absorption by the trailing electrodes due to the vertical focusing effect of the leading

electrodes. The leading electrodes referred to in the foregoing are those electrodes nearest the ion source, whereas the trailing electrodes are those electrodes nearest the ion receiver.

Inasmuch as the salient features of this invention have been described in detail with respect to one embodiment it will, of course, be apparent that numerous modifications may be made within the spirit and scope of this invention and it is not therefore desired to limit the invention to the exact details shown except insofar as they may be defined in the following claims.

What is claimed is:

1. In an apparatus used for the electromagnetic separation of ions or isotopes including a tank, a magnetic field through said tank, an ion source, a divergent arcuate ion beam the plane of which lies transverse to said magnetic field, and an ion receiver; a first group of curvilinear strip electrodes planarly nested and arranged in parallel spaced planar decks with their planar surfaces normal to said magnetic field, a second group of curvilinear strip electrodes planarly nested and arranged in parallel spaced planar decks with their planar surfaces normal to said magnetic field, the outermost edges of said first group and said second group lying symmetrically within a shield shaped magnetic projection, said second group being offset along said magnetic field with respect to said first group with the outer electrodes thereof being substantially coplanar with the outer electrodes of said first group and potential supply means impressing a different potential upon each of said groups of electrodes, thereby defining equipotential electric lens surfaces.
2. In an apparatus used for the electromagnetic separation of ions or isotopes including a tank having a magnetic field passing therethrough, an ion source, a divergent arcuate ion beam the plane of which lies transverse to said magnetic field, and an ion receiver; a first group of curvilinear strip electrodes planarly nested and arranged in parallel spaced planar decks with their planar surfaces normal to said magnetic field, a second group of curvilinear strip electrodes planarly nested and arranged in parallel spaced planar decks with their planar surfaces normal to said magnetic field, the outermost edges of said first group lying symmetrically within a shield shaped magnetic projection, the individual electrodes of said second group being offset along said magnetic field with respect to the individual electrodes of said first group, means for charging each of said groups of electrodes to a different potential, thereby defining an electrostatic lens, said groups of electrodes being symmetrically arranged with respect to the radial bisector of the ion beam arc whereby ions having equal mass to charge ratios are directed to an initial focus in the region of said receiver.
3. In an electric lens for the focusing of charged particles and disposed within a magnetic field, the improvement comprising a first set of electrodes spaced along and normal to said magnetic field and having central and end electrodes, a second set of electrodes spaced along and normal to said magnetic field and having central electrodes offset along said magnetic field with respect to the central electrodes of said first set and end electrodes substantially coplanar with the end electrodes of said first set, and power supply means impressing a potential upon said electrodes whereby said first and second sets of

electrodes define equipotential surfaces focusing charged particles passing therethrough.

4. In an electric lens for the focusing of charged particles the improvement comprising a magnetic field directed normal to the path of charged particles to be focused, a first group of electrodes divided into first and second rows aligned along the magnetic field, the electrodes of said first group being curvilinear and parallel, with the electrodes of the first row offset along said magnetic field with respect to the electrodes of the second row and all electrodes of said first group being at the same potential, and a second group of electrodes at a different potential than the electrodes of said first group and being

15

divided into first and second rows aligned along said magnetic field, individual electrodes of said first and second rows being coplanar with and adjacent the individual electrodes of the first and second rows respectively of said first group, the electrodes of said second group having the same curvature as the adjacent electrodes of said first group whereby a pair of equipotential surfaces are formed between said first and second rows of electrodes and charged particles passing perpendicularly therethrough are deflected away from the electrodes thereof.
